UNITED STATES PATENT OFFICE

166,072

ASH RECEIVING RECEPTACLE

Murray Drexler, New York, N. Y.

Application August 26, 1950, Serial No. 11,944

Term of patent 7 years

(Cl. D85—2)

To all whom it may concern:

Be it known that I, Murray Drexler, a citizen of the United States of America, residing in New York, county of New York, and State of New York, have invented a new, original, and ornamental Design for an Ash Receiving Receptacle, of which the following is a specification, reference being had to the accompanying drawing, forming part thereof.

The figure on the drawing is a perspective view of an ash receiving receptacle, showing my new design.

The dominant features of my new design reside in the upper portion thereof.

I claim:

The ornamental design for an ash receiving receptacle, substantially as shown and described.

MURRAY DREXLER.
